UNITED STATES PATENT OFFICE.

THOMAS DE Q. RICHARDSON, OF PHILADELPHIA, PENNSYLVANIA.

DESIGN FOR A BUCKLE.

SPECIFICATION forming part of Design No. 35,199, dated October 22, 1901.

Application filed May 21, 1901. Serial No. 61,313. Term of patent 14 years.

To all whom it may concern:

Be it known that I, THOMAS DE Q. RICHARDSON, a citizen of the United States, residing in the city and county of Philadelphia, State of Pennsylvania, have invented and produced a new and original Design for a Buckle, of which the following is a specification, reference being had to the accompanying drawing, forming part thereof.

16 The leading feature of my design for a buckle is a prong member having a side inclined toward the side of the frame member and prongs which are oblique to the side of said frame member.

15 The figure represents a plan view of a buckle embodying my design.

In the drawing, A designates a buckle con-

sisting of the frame member B, the prongs C, the bearings D on the frame B, and the prong member E. The side of said prong member 20 E is inclined toward the side F of the frame member. The prongs C extend from the bearings D oblique to said side F of the frame member.

Having thus described my invention, what 25 I claim as new, and desire to secure by Letters Patent, is—

The design for a buckle substantially as shown and described.

THOMAS DE Q. RICHARDSON.
